ELECTRICAL SWITCH

Henry M. Dressel, Chicago, and Kenneth C. Allison, Arlington Heights, Ill., assignors to Oak Manufacturing Company, Chicago, Ill., a corporation of Illinois

Application March 27, 1935, Serial No. 13,264

11 Claims. (Cl. 200—11)

This invention relates to electrical switches, and particularly to switches for use on radio receivers. In switching circuits from one wave band to another on radio receivers, it is desirable to have a multi-point switch which is simple, inexpensive and which will have a low and constant contact resistance throughout a long useful life. While many switches for this purpose have been devised, repeated tests have indicated that it is difficult to make a switch having the above characteristics. Most switches tend to develop a high resistance at the contact junctions after some use. The switch herein described has been found to be highly satisfactory and is herewith described in connection with the drawing wherein Figure 1 is a plan view looking down upon the top of the switch, with a part cut away; Figure 2 is a vertical sectional view of the switch on line 2—2 of Figure 1; Figure 3 is a top view down from 3—3 of Figure 2; Figure 4 is a detail.

The switch comprises a base member 1 of insulating material, such as a phenol condensate product, preferably, though not necessarily, of circular contour, and being provided with a centrally disposed bushing 2. Bushing 2 is provided with a threaded portion 3 for mounting upon a panel. Bushing 2 is maintained in place by having its end 5, turned over against a metal washer 6, which lies against base 1.

30 Circularly disposed around bushing 2 on base 1 are a plurality of stationary spring contacts 10, maintained in position by eyelets 11. Contact 10 is provided with a rectangular aperture 12, which is adapted to register with a similar aperture 13, in base 1. To prevent rotation of contact 10 with respect to base 1, the contact has two ears 15 and 16, bent down to engage the opposite sides of rectangular slot 13.

Contact 10 has one end 20 thereof formed as a soldering lug and is bent up away from base 1. The other end 21 of contact 10 is formed as a bent over spring.

The contact end 22, has lateral offset portions 23 and 24 of substantially greater width than the body portion 10. Offset portions 23 and 24 are bent downwardly toward base 1 for starting the rotor contacts thereon.

50 Mounted for rotation within bushing 2 is a shaft 30, having a reduced portion 31 and terminating in a rectangular portion 32. Shaft 30 is adapted to abut against a shoulder 33 in bushing 2 and is prevented in this manner from further translatory movement in an upward direction as seen in Figure 2. Mounted on the rectangular portion 32 of shaft 30 are three members 35, 36,

and 37. 35 is preferably a circular disc of metal. Member 36 is preferably of insulating material similar to base 1 and carries a plurality of movable contacts 40. These contacts are preferably formed as small slugs, having tips 41 and 42 and bent along the arc of a circle as shown in Figure 1. Member 36 is provided with a plurality of circumferentially disposed slots 43 and 44, of predetermined size, to accommodate tips 41 and 42 of contacts 40. These tips are adapted to be staked at 43a to maintain the contacts in member 36. The bottom part of contact 40 is preferably formed with a centrally projecting portion 45 for indexing, flanked on each side by a curvilinear portion 46. The relation of movable contact 40 and stationary contact 10 is such that tip 22 of contact 10 tightly presses against curved portion 46 of the movable contact.

To maintain the rotor assembly intact, member 37, which is preferably of metal, has a tongue 50 bent down through a slot in member 36. Member 37 also has a long tongue 51, bent down and projecting through a slot in member 36 and having its free end adjacent base 1. It is obvious that rotor member 36 is tightly locked to outer member 37. The assembly is maintained intact by spinning the end 53 of shaft 30 over against member 37.

Washer 6 has one side thereof provided with a slot 60 whose angular extent is a function of the angle in which the entire rotor is to turn. Depending tongue 51 of the rotor assembly is long enough to project into slot 60 and engage the side walls 61 of the washer. In order to lock washer 6 against rotation, ears 62 are bent down into suitable openings in insulating member 1.

What is claimed is:

1. An electric switch comprising an insulating stator disk, a shaft journaled therein, an insulating rotor disk carried by said shaft, spring contacts carried by said stator disposed on the arc of a circle concentric with said shaft, contacts carried by said rotor circularly disposed around said shaft and cooperating with stator contacts, each rotor contact being adapted to complete a circuit between two adjacent stator contacts in one position of the rotor, said rotor contacts comprising elongated metal members, means for mounting said rotor contacts along an edge thereof on said rotor in proximity to said spring contacts, said rotor contacts having a free edge divided into two contacting surfaces, each one adapted to be engaged by a spring contact and an irregularity in said edge between said

adjacent contacting surfaces adapted to co-act with a spring contact for indexing said rotor.

2. An electric switch comprising an insulating stator disk, a plurality of stationary contacts disposed thereon on the arc of a circle, a shaft rotatively mounted in said disk at the center of said circle, a rotor carried by said shaft, contacts carried by said rotor, a metal washer disposed adjacent said rotor, a finger integral with said washer extending toward said stator disk, and a stationary washer carried by said stator having a slot into which said finger extends for defining the range of adjustment of said rotor.

3. An electric switch comprising an insulating disk having a plurality of contacts disposed thereon on the arc of a circle, a shaft concentric with said circle, means for rotatively supporting said shaft, a washer having an extended slot therein surrounding said shaft and supported by said means, a rotor carrying movable contacts cooperating with said stationary contacts, means including a washer for mounting said rotor on said shaft, and a finger depending from said rotor washer extending toward said first named washer and penetrating into said slot for defining the angular extent of travel of said rotor.

4. An electric switch comprising an insulating stationary disk, a shaft rotatively mounted therein, contacts carried by said disk on one of its flat faces and disposed around said shaft, a rotor mounted on said shaft comprising an insulating disk having a flat face disposed adjacent to and parallel to said first disk, means for locking said rotor disk on said shaft, said locking means including a finger extending from said rotor toward said stationary insulating disk, a stationary member on said stationary disk having a slot therein engaged by said finger for limiting rotor movement, contacts circularly disposed on said rotor on the flat face nearest said first disk, said first named contacts having spring portions facing said rotor disk and said rotor contacts being rigid members having no spring thereto and adapted to engage said first named contacts at the spring portions only.

5. An electric switch comprising a flat stator insulating disk, a shaft rotatively mounted therein, contacts mounted on said disk and disposed around said shaft on the arc of a circle concentric therewith, a flat insulating rotor disk carried by said shaft, contacts carried by said rotor disk adapted to co-operate with the stator contacts, a metal washer secured to said stator disk and forming a bearing therein for said shaft, an additional metal washer rigidly secured to said shaft and abutting the outer surface of said rotor disk, a finger depending from said additional washer through said rotor disk toward said first washer, said first washer being provided with a slot into which said finger extends whereby the movement of said shaft and rotor is limited.

6. An electric switch comprising a stator insulating disk carrying a plurality of spring contacts, a shaft rotatively carried in said disk, a rotor insulating disk carried by said shaft, said rotor disk being provided with a plurality of elongated spaced slots disposed on the circumference of a circle having its center concentric with the shaft, and elongated rigid contacts mounted in said slots, said rotor contacts being mounted on their edge, the mounting edge of each contact

having at least one protuberance adapted to project through said slot and being deformed on the free edge thereof to maintain said contact on said rotor disk.

7. An electric switch comprising a flat insulating stator disc, a shaft rotatively mounted therein, said disc having a plurality of rectangular apertures therethrough on the circumference of a circle concentric with said shaft, a contact disposed at each aperture, each contact having a 10 registering similar aperture with a portion of the contact material depending through said stator disc adjacent at least one of the rectangular sides of the aperture, a round eyelet for each contact passing through the registering apertures for 15 maintaining each contact in position, a slotted member carried by said stator disc, a rotor member carried by said shaft facing said stator disc and provided with a plurality of contacts and a member carried by said shaft provided with a 20 finger depending toward said stator disc and co-operating with said slotted member for defining the limits of rotor travel.

8. An electric switch comprising a flat insulating disc, a bushing mounted in said disc and extending therethrough, a shaft rotatively mounted in said bushing, a series of rectangular apertures in said disc disposed around said shaft, on the arc of a circle concentric with said shaft, a spring contact carried by said disc at each aperture, 30 said spring contact having a body portion adapted to overlie said disc provided with at least one tongue extending through said aperture at a side thereof for holding said contact against rotation, said body portion of said contact extending into a spring contact portion, a rotor disc carried by said shaft, a plurality of elongated contact slugs disposed on said rotor disc to cooperate with said stator contacts, said slugs being mounted along an edge with the opposite edge as 40 the contacting surface, said edges lying on the arc of a circle concentric with said shaft.

9. The switch of claim 8 wherein said bushing carries a slotted member, and wherein said shaft carries a member having a finger extending into 45 the slot of said slotted member for defining the limits of rotor travel.

10. An electric switch comprising an insulating disc, a shaft rotatively carried thereby, a plurality of spring stator contacts disposed on said disc 50 on the arc of a circle concentric with said shaft, an insulating rotor disc carried by said shaft and facing said stator disc, and a plurality of contact slugs disposed on said rotor disc cooperating with said stator contacts, each slug comprising an 55 elongated metallic member with a plurality of projections extending from one of the long edges, said slug being secured to said disc by having said projections extend through apertures in said disc and deforming said projections on the opposite side of said disc to lock said slug in position, said long edges of said slugs lying on the arc of a circle concentric with said shaft.

11. The switch of claim 10 wherein each slug has a center projection on the other long edge 65 and wherein said spring contacts are adapted to cooperate with said other long edge with said projection adapted to provide an indexing action.
